[57] **CLAIM**

The ornamental design for a saddle, substantially as shown and described.

DESCRIPTION

FIG. 1 is a perspective view taken from the front, top and left side of a saddle showing my new design, with the left side fender removed and portions broken away for convenience of illustration; and

FIG. 2 is a perspective view taken from the rear and left side thereof.

The right side is a mirror image of the left side shown in FIG. 2 and the bottom of the seat portion is plain.
